Des. 895

J. W. Gibbs, of Albany, N.Y.
Letters Patent No 895. Dated June 16, 1857.

The schedule referred to in these Letters Patent, and making part of the same.

To all whom it may concern:

Be it known that J. W. Gibbs, of Albany, in the County of Albany in the State of New York, have invented a new and useful design for an Elevated Oven Stove, and I do hereby declare that the following is a full, and exact description thereof, reference being had to the accompanying drawings and to the letters of reference marked theron:

Fig: A, in the accompanying drawings represents the ornamented front of oven of an Elevated Oven Cook Stove.

Fig: B, represents the front and front doors, also front door mouldings and ornaments, also ornaments on each end of the front, and over the doors of an Elevated Oven Cook Stove, all these ornaments designated by the fig: 2. also ornaments on the doors marked 2.

Fig: C, represents the ornamented door of said oven of an Elevated Oven Cook Stove, the moulding and molding ornaments being the same as on the front doors, as heretofore described and designated, by the fig: 2. A. G. M.

What I claim as my invention and desire to secure by Letters Patent, is the combination of ornaments as herein described, the whole forming an original design for an Elevated Oven Cook Stove.
